UNITED STATES PATENT OFFICE

ROY O. ALLEN, OF ATHENS, PENNSYLVANIA, ASSIGNOR TO INGERSOLL-RAND COMPANY, OF JERSEY CITY, NEW JERSEY, A CORPORATION OF NEW JERSEY

IMPLEMENT RETAINER FOR PNEUMATIC TOOLS

Application filed April 2, 1928. Serial No. 266,528.

This invention relates to pneumatic tools, but more particularly to implement retainers for tools of the hammer type in which the working implement extends into the end 5 of the cylinder to receive the blows of the hammer piston.

The objects of the invention are to prevent ejection of the working implement from the cylinder, to form a yieldable abutment 10 for the working implement and to enable the retainer to be readily mounted on or removed from the tool.

Other objects will be in part obvious and in part pointed out hereinafter.

15 In the drawings accompanying the specification and in which similar reference characters refer to similar parts,

Figure 1 is a sectional elevation of the front end of a pneumatic tool having the 20 invention applied thereto,

Figure 2 is a transverse view taken through Figure 1 on the line 2—2 looking in the direction indicated by the arrows,

Figure 3 is a perspective view of the front 25 end of a cylinder,

Figure 4 is a perspective view of the locking ring, and

Figure 5 is a similar view of the rearward 30 end of the retainer sleeve.

Referring to the drawings, the invention is shown applied to a pneumatic tool having a cylinder A into which extends a shank B of a working implement C. The shank B is guided by a bushing D inserted into the front end of the cylinder A and extends into the front end of the cylinder to receive the blows of a hammer piston E reciprocable in the cylinder A.

At the juncture of the shank B and the body portion of the working implement C is a collar F which abuts the front end of the cylinder A to limit the distance which the shank B may extend into the cylinder.

In accordance with the present invention, 45 means are provided for preventing the ejection of the working implement C from the cylinder A. These means comprise a sleeve G having a plurality of rows of arcuate ribs H in the rearward portion thereof to interlock with arcuate ribs J on the front end of

the cylinder A. The ribs J are arranged in longitudinal rows about the periphery of the cylinder and the adjacent rows of ribs J are spaced so with respect to each other that the ribs H of the sleeve G may pass 55 readily therebetween.

At a point forwardly of the innermost rib H of the sleeve G is a shoulder K which when the sleeve G is placed on the cylinder A may abut the front end of the cylinder 60 and thus serve to locate the ribs H with respect to and guide them into engagement with the ribs J of the cylinder.

The means provided for the working implement C in the cylinder A comprises in 65 this instance a rubber buffer L which, when used for working implements having an enlarged cutting bit, such as a drill steel or a clay shovel, may be split to enable said buffer to be readily disposed about the body 70 portion of the implement. The buffer L is preferably of a size to closely embrace the body portion of the implement and is seated on a bushing O disposed within a bore P in the front end of the sleeve G. When used 75 for retaining implements of the type in which it becomes necessary to split the buffer L, the bushing O may be formed in half sections Q to enable them to be disposed about the body portion of that type of working 80 implement.

In order to insure against the accidental removal of the sleeve G from the cylinder A, the cylinder is provided with a reduced portion S rearwardly of the ribs J. On this 85 reduced portion is slidably disposed suitable locking means consisting in this instance of a ring portion T having integral fingers U. The number of the fingers U may equal that of the rows of ribs J and H. These fingers 90 may be of substantially the same width as the space between adjacent rows of ribs between which said fingers extend to act as an abutment therefor.

In cross section the ring portion T may be 95 of semi-circular shape so that it may be readily grasped by the operators for moving it into or out of the locking position. The inner surfaces V of the fingers U may snugly engage the periphery of the cylinder A and 100

at the rearward end of the ring T are introverted flanges W which preferably also bear against the surface of the cylinder to hold said ring against lateral movement with respect to the cylinder. Between the flanges W are formed recesses X to permit the passage of the ribs J therethrough.

Although the fingers U of the ring T may be adapted to maintain the ring T in the locking position, other means, such as a spring Y, may be disposed about the reduced portion S of the cylinder to seat with one end against the rearward end of the ring T and with its other end against a shoulder Z at the rearward end of the reduced portion S.

In assembling the retainer on the cylinder, the spring Y and the ring T may first be placed in the reduced portion of the cylinder.

After the working implement C has been inserted in the cylinder, the cushioning means, such as the buffer L, the bushing O and the collar sections R, may be disposed about the implement C and the sleeve G may then be moved in position to embrace the cushioning means. Continued rearward movement of the sleeve will enable the ribs H to pass between the ends of the ribs J until the shoulder K of the sleeve abuts the front end of the cylinder. If then the sleeve G is rotated a partial revolution, the ribs H will be moved into engagement with the ribs J. Thereafter the ring T may be released and the spring Y will move said ring in a forwardly direction to enter the fingers U between the adjacent rows of interlocked ribs J and H and will be held in this position by the spring unaffected by the vibration of the tool.

The mode of assembling may vary with the specific type of working implement used. That described is based on the assumption that a tool of the coal pick type is used. In such case it is of course possible for the sleeve G to pass over the bit end of the tool. When used with tools in which this is not possible, as for instance, a clay spade or drill steels, the sleeve G may be placed on the working implement from the rearward end of the working implement and the other operations will follow as described.

The present invention is particularly desirable for use in connection with pneumatic tools in which frequent changes of the working implements are required. As will be readily seen, the retaining device may be quickly removed from the cylinder or placed thereon. It is of sturdy construction and therefore fully capable of withstanding any rough usage to which it may be subjected and is adapted for use in connection with any type of working implement which tools of this type are intended to actuate.

I claim:

66. In an implement retainer for pneumatic

tools, the combination of a cylinder and a working implement extending into the cylinder, a sleeve for retaining the implement in the cylinder, arcuate ribs on the cylinder and in the sleeve adapted to interlock for holding the sleeve on the cylinder, a shoulder in the sleeve to abut the end of the cylinder for guiding the ribs into engagement with each other, a ring 70 slidable on the cylinder having integral fingers to extend between the ribs for holding the sleeve against rotation with respect to the cylinder, a spring seated with one end against the ring and with its other end against the cylinder to maintain the fingers 75 between the ribs, and yieldable means in the sleeve for limiting the forward movement of the working implement.

In testimony whereof I have signed this specification.

ROY O. ALLEN.
